CLAIM

The ornamental design for a combined monorail train and track toy, as shown and described.

DESCRIPTION

FIG. 1 is a perspective view of a combined monorail train and track toy which embodies my design;

FIG. 2 is a front elevational view thereof, the rear elevational view thereof being a mirror image thereof;

FIG. 3 is a right side elevational view thereof;

FIG. 4 is a left side elevational view thereof;

FIG. 5 is a top plan view thereof; and,

FIG. 6 is a bottom view thereof.

The track is fragmentarily shown for ease of illustration and it is understood that the pattern uniformly repeats itself throughout the length of the track.
